UNITED STATES PATENT OFFICE.

JOHN W. ANDREE, OF GLENDALE, AND LEO J. KRAPS, OF LONG BEACH, CALIFORNIA.

BOILER FURNACE.

Application filed November 19, 1923. Serial No. 675,543.

To all whom it may concern:

Be it known the we, JOHN W. ANDREE, a citizen of the United States, and a resident of Glendale, county of Los Angeles, State of California, and LEO J. KRAPS, a citizen of the United States, and a resident of Long Beach, county of Los Angeles, State of California, have invented new and useful Improvements in Boiler Furnaces, of which 10 the following is a specification.

This invention has to do with a furnace, and has particular reference to a boiler furnace; it being an object of this invention to provide a simple, effective and practical 15 boiler furnace.

In certain localities gas is available as fuel for boilers, and the like, making it practical to equip boilers with furnaces for burning such fuel. It is desirable for 20 boiler furnaces equipped to burn gas to also be equipped to burn oil or like fuel in addition to or in place of gas.

It is an object of this invention to provide a simple, efficient and effective gas 25 burning furnace suitable for a boiler, or the like.

Another object of this invention is to provide a practical, efficient furnace for burning gas or oil, or both.

Another object of this invention is to provide a simple, effective air control for a furnace of the character above referred to.

The various objects and features of our invention will be best and more fully understood from the following detailed description of a typical preferred form and application of the invention, throughout which description reference is had to the accompanying drawings, in which:

Fig. 1 is a sectional view showing a typical steam boiler equipped with the furnace provided by this invention;

Fig. 2 is an enlarged detail view of the furnace as it is shown in Fig. 1;

Fig. 3 is a plan view of the furnace, taken as indicated by the line 3—3 on Fig. 2, showing certain of the parts broken away; and

Fig. 4 is an enlarged detail sectional view 50 of one of the gas burners.

The furnace provided by our present invention is particularly suited for steam boilers, however, it is not to be understood as limited to any specific type, form or 55 make of boiler. For the purpose of facil-

tating a full and clear understanding of our invention we will herein describe it as applied to or used in connection with a popular type of steam boiler familiar to those skilled in the art, and in connection with which our invention has been actually employed to great advantage.

The boiler illustrated in the drawings is of the water tube type, and includes, generally, three steam and water drums 10, 11, and 12, a mud drum 13, and three banks of tubes 14, 15, and 16, connecting drums 10, 11, and 12, respectively, with the mud drum 13. The steam spaces of the drums 10, 11, and 12, are connected by steam circulating pipes 17. A super-heater 18 is located between the first and second banks of tubes and is connected with the steam space of the middle drum 11 by a steam pipe 19. The boiler is mounted in a typical setting 13 which is substantially rectangular in form, and includes, generally, a base 20, side walls 21, a rear wall 22, a front wall 23, and a top 24.

The furnace, in accordance with our present invention, is located at the lower forward portion of the boiler and setting between the front wall 23 of the setting and a back partition 25 extending between the base 20 and the forward side of the mud drum 13. The base of the setting forms what we will term the floor, or bottom of the furnace.

The furnace includes, or is equipped with, one or more liquid fuel burners 26, located 90 at the rear of the furnace, that is, at or immediately in front of the back 25. The burners 26 are spaced above the furnace floor and are preferably faced forward or toward the front of the boiler and are 95 tilted somewhat upwardly. The supply pipes 27 for the burners 26, for instance, fuel pipes and air or steam pipes, extend downwardly from the burners and along the floor of the furnace to the front of the 100 boiler where they are equipped with suitable control valves 28.

The invention provides one or more blocks of gas burners at the forward part of the furnace. The blocks of gas burners are 105 spaced above the furnace floor and extend inwardly or rearwardly from the front wall 23 of the boiler mounting. The blocks of burners are preferably inclined slightly so that their rear ends are somewhat lower than 110

their forward ends. The blocks are proportioned and arranged so that they extend to about the middle of the furnace, leaving a substantial space between them and the 5 liquid fuel burners 26.

Each block of burners includes a body 30 of refractory material, having a plurality of vertical openings 31 through it. Burner tubes 32 are located below the body 30 and 10 extend upwardly a short distance into the openings 31. The burner tubes 32 are preferably formed of metal so that they are comparatively thin, making it practical to arrange them much closer together than 15 would be possible if they were formed of a refractory material. By extending the upper ends of the burner tubes a short distance into the body 30 there is a substantial amount of refractory material above them 20 protecting them from the heat of the furnace.

In the preferred form of construction the body 30 is not built up of bricks, or like members, but is formed as a unit around 25 the upper ends of the burner tubes, the openings 31 being cored, or otherwise formed. The rear ends of the blocks of burners are supported by props 35 extending upwardly from the furnace floor. In addition to this support the body 30 is supported at numerous points by suitable transverse 30 supporting bars 36.

The burner tubes are supplied with gas 35 from suitable distributing arms and are open at their lower ends to receive air. The distributing arms 37 extend horizontally into the burner tubes and are provided with openings 37^a which discharge the gas upwardly in the burner tubes. The distributing arms 37 are formed in groups, each group including four arms 37 arranged as 40 illustrated in Fig. 3 of the drawings. The units of distributing arms are connected with main distributing pipes 39 that extend 45 rearwardly under the burner tubes from the front of the setting. The main distributing pipes 39 may be connected together in pairs at their forward ends to be supplied with gas from the supply pipes 40. The forward 50 ends of the main distributing pipes are supported by a transverse supporting member or beam 41 which also supports or aids in supporting the forward ends of the burner blocks. The supply pipes 40 are provided 55 with suitable control valves 42.

In the space between the liquid fuel burners 26 and the blocks of gas burners we provide a grate 45 of brick or other suitable material. The grate is located 60 somewhat below the level of the burners 26 and extends to the rear ends of the blocks of gas burners. The grate distributes the air and supplies it to the liquid fuel burners at the proper velocity.

65 The front wall 23 of the boiler setting is

provided, adjacent the base, with openings 46 for admitting air to the furnace. The openings 46 are located so that they admit the air to the furnace below the blocks of gas burners.

70

The present invention provides a damper 48 operable to direct and control the air entering the furnace through the openings 46. In accordance with the preferred form 75 of the invention the damper is in the form of a plate, or a plurality of plates, as circumstances may require, located between the blocks of gas burners and the furnace floor. The damper is pivotally mounted at the rear or inner ends of the blocks of gas burners, or at the point of connection between the blocks of gas burners and the grate 45, so that its forward end is movable between the furnace floor and a part 49 at the forward ends of the blocks of gas burners.

80

The part 49 may, as we have illustrated in the drawings, be in the form of an apron extending downwardly from the bodies 30 of the blocks of gas burners and supported by the brace or beam 41. When the damper is down or has its forward portion lowered to the furnace floor the air entering the furnace through the openings 46 is all directed to the gas burners so that it passes upwardly through the burner tubes. When the damper is in the up position or is raised so that its forward portion engages the part 49 all of the air entering the openings 46 is directed to the grate 45 for the burners 26. When the damper is in an intermediate 90 position, that is, between its raised and lowered positions, it will divide the air entering the furnace and will direct part of it to the gas burners and part of it to the grate 45 for the oil burners.

95

In practice we provide the damper 48 with an operating mechanism so that it is convenient to operate or control. The operating mechanism illustrated in the drawings includes an operating handle 60 connected to a lever 61 which is fast on a rotatable shaft 62. A second lever 63 is fast on the shaft 62 and is connected with the damper by a link 64. Movement of the handle 60 will cause rotation of the shaft 62 which, through the lever 63 and link 64, will cause movement of the damper.

105

It is believed that the operation of the furnace will be fully understood from the foregoing description, it being apparent how air from the openings 46 may be directed to the gas burners to support combustion of gas supplied by the supply pipes 40, or may be directed to the grate 45 so that it will support combustion of liquid fuel issuing from the burners 26. It will be apparent that the furnace can be operated on gas alone, on liquid fuel alone, on both gas and liquid fuel simultaneously, and that it may be changed over from one kind 110

115

120

130

of fuel to the other without shutting down the boiler.

We have found by actual practice that the arrangement and construction of the blocks of gas burners is particularly efficient and effective. By constructing, locating and arranging the burner tubes and the gas supply arms therefor in the manner above described the tubes can be arranged close together getting a maximum number in a given space. Further, we have found that by locating the gas burners at the forward portion of the furnace the first or front bank of boiler tubes is not overheated, the gases reach the super-heater at a comparatively high temperature, and that the general efficiency of the boiler is high.

Having described only a typical preferred form of our invention we do not wish to limit ourselves to the specific details hereinabove set forth but wish to reserve to ourselves any changes or variations that may appear to those skilled in the art or fall within the scope of the following claims.

Having described our invention, we claim:

1. In a furnace of the character described, a liquid fuel burner located at the rear of the furnace, a plurality of gas burners located in the forward portion of the furnace so that there is a substantial space between them and the rear of the furnace to admit air to the liquid fuel burner, and means for directing air admitted to the furnace to the liquid fuel burner or to the gas burners.

2. In a furnace of the character described,

a liquid fuel burner located at the rear of the furnace, a plurality of gas burners located in the forward portion of the furnace so that there is a substantial space between them and the rear of the furnace to admit air to the liquid fuel burner, and control means for the air admitted to the furnace whereby it can all be directed to the gas burners or to the liquid fuel burner or can be divided between them.

3. A furnace of the character described including, a bottom, front and rear walls, a liquid fuel burner at the rear wall, a block of gas burners in the forward portion of the furnace spaced above the bottom, and a damper pivotally mounted at the rear end of the block so that its outer part is movable between the bottom and the front end of the block.

4. A furnace of the character described including, a bottom, front and rear walls, a liquid fuel burner at the rear wall, a block of gas burners in the forward portion of the furnace spaced above the bottom, a damper pivotally mounted at the rear end of the block so that its outer part is movable between the bottom and the front end of the block, and means for operating the damper from the front of the furnace.

In witness that we claim the foregoing we have hereunto subscribed our names this 6th day of November 1923.

JOHN W. ANDREE.
LEO J. KRAPS.

Witness:

IDA L. WESTLAKE.
